UNITED STATES PATENT OFFICE.

ERNST BROCKMANN, OF ELLRICH, GERMANY.

SHOW-STAND.

SPECIFICATION forming part of Letters Patent No. 447,658, dated March 3, 1891.

Application filed July 23, 1890. Serial No. 359,653. (No model.)

To all whom it may concern:

Be it known that I, ERNST BROCKMANN, a subject of the King of Prussia and Emperor of Germany, a resident of Ellrich, in the Province of Saxony, German Empire, have invented certain new and useful Improvements in Show-Stands, of which the following is an exact description.

The object of my invention is to provide a stand for exhibiting objects of sale in show-windows or shops, with an especial view to economy of space and facility in reaching the articles.

In order to make my invention more clear, I refer to the accompanying drawings, in which similar letters denote similar parts throughout the several figures.

Figure 1 is an end elevation of the stand. Fig. 4 is a front elevation, partly in section, of Fig. 1. Fig. 2 is a section through the top guide-rail, drawn to a larger scale. Fig. 3 is a joint at the end of top guide-rail. Fig. 5 is an end elevation of the stand, showing a modified form of the displaceable frame. Fig. 6 is a front view of the same frame, the shelf of it being in vertical position. Fig. 7 is another front view of the same frame, the shelf being in horizontal position. Fig. 8 is a modification of the fastening device for the shelf.

Any number of shelves F', Figs. 1 and 4, according to requirement, are secured by any means to a frame F, Figs. 1 and 4, the whole frame adapted to be drawn out. For this purpose guide-rails e are attached to the upper part of the frame A and project forward. These projecting rails are supported by a cross-piece A', which is stayed to the main frame A by a tie A³, hooking over a beam on the said frame A and attached to the cross-bar A' by a bolt e³. The back ends of those rails are supported in a suspending-hook e⁶, suspended on the back cross-bar A² of the frame A.

The frames F F contain the guide-irons f', in which the rollers f f run on rails e e. In order that the frames may be guided perfectly securely on being drawn out, the angle-irons e' e', running parallel to and lying over the guide-rails e e, are attached at their front ends to the cross-bar A' and rail e by means of bolts e³ and irons e², Fig. 3, said iron e² having a projection through which bolt e³ passes,

while the back ends of these angle-irons are attached to the guide-rails by straps e⁵. The 55 guide-irons f' of the frames F pass over this angle-iron e', thus insuring a safe guiding of the frames F. In order to relieve the top projecting guide-bar e of the weight of the whole frames, bottom or ground rails e⁸ are provided, 60 on which the frames run by means of rollers f² in straps f³. The shelves F' may be made vertically adjustable sideways, the hooks e⁶ being movable in their grooves e⁷ at the back, while the front cross-beam A' is provided 65 with holes, Fig. 4, into which the bolts e⁸ may be placed. The ground-rails need only be shifted into the required position, and, if desirable, screwed onto the floor.

Instead of providing the frames with 70 shelves, they may be modified in such a manner that they contain one large shelf or frame, which may be made to rotate round a horizontal axle, Figs. 5 to 8, such as frame G, Fig. 5, which may stand on end in the main frame, 75 and on the articles being inspected the frame F will be run or drawn out and the shelf or frame G turned into a horizontal position by means of the cogged segment p and pinion p', turned by handle P. The frame G will have 80 a counterbalance-weight q on its lower end to hold it in its vertical position. Instead of a cogged segment, a segment p², provided with a slit, may be substituted and the frame fixed in the same by means of a set-screw p³. 85

Having thus fully described my invention, what I desire to secure by Letters Patent of the United States is—

The combination of a frame A, having top guiding-rails e, guiding angle-irons e', projecting out in front and connected to said frame and cross-bar A' by straps e² e⁴ e⁵ and bolt e³, tie A³, and hook e⁶ of the frames F F, containing adjustable shelves F' F' and supported on upper guide-rails e e' by rollers f f 90 and straps f' f' and on ground-rail e⁸ by rollers f² f², said frames, together with guide-rails, being adjustable sideways in frame A A', in the manner described.

In testimony whereof I have signed this 100 specification in the presence of two subscribing witnesses.

ERNST BROCKMANN.
